UNITED STATES PATENT OFFICE.

CLARK N. LOWELL, OF BELLAIRE, OHIO.

LOCK.

1,169,659.

Specification of Letters Patent. Patented Jan. 25, 1916.

Application filed October 13, 1915. Serial No. 55,681.

To all whom it may concern:

Be it known that I, CLARK N. LOWELL, a citizen of the United States, residing at Bellaire, in the county of Belmont and State 5 of Ohio, have invented certain new and useful Improvements in Locks; and I do hereby declare the following to be a full, clear, and exact description of the invention, such as will enable others skilled in the art to 10 which it appertains to make and use the same.

This invention relates to locks and has for its primary object to provide a simple and efficient lock embodying a sliding bolt and 15 means for projecting the bolt from either end of the lock casing.

Another object is the provision of a lock embodying a sliding bolt operable by a pinion or gear wheel adapted to be moved 20 out of mesh with the sliding bolt and locked against rotary movement.

With these and other objects in view, the invention consists in the novel construction, arrangement and formation of parts as will 25 be hereinafter specifically described, claimed and illustrated in the accompanying drawing, in which:—

Figure 1 represents a side elevation of the improved lock partly in section, Fig. 2 represents a vertical central sectional view therethrough, and Fig. 3 represents a fragmental detail sectional view on the line 3—3 of Fig. 1.

Referring to the drawing in detail, wherein 35 similar reference numerals designate corresponding parts throughout the several views, the numeral 5 designates the body of the casing including a removable front plate 6. A plurality of bearings or supports 7 are 40 rigidly secured in the bottom of the casing 5 and slidably support the sliding bolt 8 adapted to be projected through apertures 8^a formed in the opposite ends of the casing 5. A plurality of gear teeth 9 are formed integral with the upper edge of the bolt 8 and project upwardly therefrom. A shaft 10 is 45 rotatably and slidably mounted in apertures 11 formed approximately at the center of the side walls of the casing and handles or 50 knobs 12 are rigidly secured to the opposite exposed ends thereof. One end of the shaft 10 is normally retained in extended position by the tension of a spring 13 engaged between the removable front plate 6 of the casing 55 and the adjacent knob 12 and being partially inclosed by a tubular extension or

sleeve 14 formed integral with the front plate 6.

A pinion or gear wheel 15 is rigidly secured against sliding and rotary movement 60 upon the shaft 10 and is adapted to be moved longitudinally with the latter into mesh with the teeth 9 of the bolt 8, whereby the latter may be adjusted longitudinally within the casing 5. As clearly illustrated 65 in Fig. 2, the slideable bolt is mounted adjacent one side wall of the casing 5, while the gear wheel 15 is normally retained in engagement with the opposite side wall or front plate 6 by the tension of the spring 13 70 thus retaining the pinion or gear wheel out of mesh with the teeth 9 of the bolt.

A plurality of lugs 16 are formed integral with the front plate 6 and are so arranged that when the gear wheel 15 is moved forwardly under the influence of the spring 13 75 out of mesh with the teeth of the bolt 8, the lugs 16 are received between the teeth of the gear wheel 15, thus positively locking the latter together with the shaft 10 against rotary movement.

A locking member 17 is slidably mounted against the inner face of the removable front wall 6 and is provided with an angular end 18 projecting forwardly through a slot 85 19 formed in the wall 6 whereby the locking member may be moved longitudinally to engage or disengage the offset inner end 20 thereof with the gear wheel 15 to lock the latter out of mesh with the teeth 9 of the 90 bolt 8.

What I claim is:

1. A lock including a casing, a bolt slidably mounted in said casing, a gear wheel associated with said bolt for actuating the 95 latter, means normally retaining said gear wheel out of coöperative relation with said bolt, and means for positively locking said gear wheel out of coöperative relation with said bolt.

2. A lock including a casing, a bolt slidably mounted in said casing, a shaft slidably and rotatably mounted in said casing, a gear wheel keyed upon said shaft, and movable into and out of coöperative relation with 105 said bolt, means normally retaining said shaft in extended position, and means for locking said gear wheel out of coöperative relation with said bolt.

3. A lock including a casing, a bolt slidably mounted in said casing, a gear wheel associated with said bolt for actuating 110

the latter, means normally retaining said gear wheel out of coöperative relation with said bolt, and means operable independently of said retaining means and extended exteriorly of said casing for positively locking said gear wheel out of coöperative relation with said bolt.

In testimony whereof I affix my signature in presence of two witnesses.

CLARK N. LOWELL
